UNITED STATES PATENT OFFICE.

HENRY H. CUMMINGS, OF NEWTON, MASSACHUSETTS, ASSIGNOR TO UNION LOCK STITCH COMPANY, OF BOSTON, MASSACHUSETTS, A CORPORATION OF MAINE.

AUTOMATIC PRESSER-FOOT-LIFTING MECHANISM.

No. 891,210.

Specification of Letters Patent.

Patented June 16, 1908.

Original application filed August 19, 1904, Serial No. 221,378. Divided and this application filed June 11, 1907.
Serial No. 378,394.

To all whom it may concern:

Be it known that I, HENRY H. CUMMINGS, a citizen of the United States, residing at Newton, in the county of Middlesex, State 5 of Massachusetts, have invented a certain new and useful Improvement in Automatic Presser-Foot-Lifting Mechanisms, of which the following is a specification, reference being had therein to the accompanying drawings.

Sewing machines of certain classes are furnished with mechanism comprising, essentially, a clamp coöperating with the presser-bar of a machine, and actuating means for 15 the said clamp acting in the operation of the machine to cause the clamp to grip or become engaged with the said presser-bar and then move the latter in the direction of the length thereof. Such mechanism is employed, for instance, for the purpose of effecting automatically the lifting of the presser-foot alternately with the formation of the 20 stitches in the working of a sewing machine. The present invention has reference to mechanism of the general character aforesaid.

It consists in the combination with the presser and presser-bar of a sewing machine, or the like machine, of an improved clamp, and improved clamp-operating means.

The invention is a division of that forming 30 the subject of my application for United States Letters Patent for improvements in presser foot lifting mechanism, filed August 19, 1904, Serial No. 221,378, on which Letters Patent were granted July 2, 1907, 35 No. 858,858, and in which the features of the clamp and its operating means are claimed more broadly.

It will be explained with reference to the 40 drawings, in which is illustrated an embodiment thereof, and in the course of the description of the said embodiment the various objects and advantages thereof will be set forth.

In the drawings,—Figure 1 shows in end elevation the head of a sewing machine having the said embodiment of the invention applied thereto. Fig. 2 is a view thereof mainly in vertical section in the plane indicated by the dotted line 2, 2, Fig. 1, looking in the direction indicated by the arrows at the ends of such line. Fig. 3 is a view thereof mainly in vertical section in the plane indicated by the dotted line 3, 3, Fig. 1, look-

ing in the direction indicated by the arrows 55 at the ends of such line. Fig. 4 is a view in horizontal section in the plane indicated by the dotted line 4, 4, Fig. 3, looking in the direction indicated by the arrows at the ends of such line. Fig. 5 shows the clamp-device 60 separately in side elevation.

Having reference to the drawings,—a presser-bar is shown at 1, the presser-foot attached to the lower end thereof being indicated at 2. The presser-bar is mounted, as 65 usual, in guide-bearings in the upper and lower portions of the head 3 of a sewing machine at the outer extremity of the arm or gooseneck 4 forming part of the frame of the said machine. To cause the presser-foot to 70 bear against the material beneath the same, a depressing spring is applied in connection with the presser-bar, as usual. The depressing spring in the present instance is a spiral-spring 5, Figs. 1, 2 and 3. It is confined between a block or collar 6, fast upon the upper end of the presser-bar above the top of the head 3, and a stationary upper collar 7. For the purpose of enabling the tension of the 75 said depressing-spring 5 to be varied as required, in order to adjust the pressure of the presser-foot upon the material beneath it, the upper collar 7 is provided upon the lower end of a screw 8, the threaded stem of the latter being fitted within an interiorly-threaded hole that is tapped through the horizontal arm of a bracket 9, the said bracket being fixed to the head 3 and rising therefrom. By turning the screw 8 in one direction or the other the collar 7 is lowered 80 or raised as may be necessary, and the tension of the spring is thereby varied in proportion as the spring 5 is compressed or relieved from compression. The screw 8 is provided with a lock-nut 81 to prevent accidental loss 85 of the adjustment thereof. In order to prevent the presser-bar and presser-foot from turning so as to swing the latter into an improper position, the collar 6 is provided with an extension 61 that is slotted as indicated in 90 Fig. 3 to fit the upright stem of the bracket 9. The said slotted extension is free to slide up and down the said upright stem, and hence the vertical movements of the presser-bar are not interfered with, but lateral displacement 95 of the presser-foot in consequence of rotary movement of the presser-foot and presser-bar around the axis of the latter is obviated.

100

105

To assist in alining the screw 8 and collar 7 with the presser-bar, and in preventing accidental shift horizontally of the horizontal arm of bracket 9 by which said screw is carried, the opposite sides of the upright stem of the said bracket are flattened, as indicated at 91, Figs. 2 and 3, for engagement with the side-walls of the slot in the extension of collar 6. The lower end of the stem of bracket 10 is received in a socket 92 in the top of head 3, see Fig. 3, and removably secured therein by means of a clamping-screw 93, Fig. 2. The loosening of the said clamping-screw, and removal of the bracket affords opportunity to withdraw the presser-bar from its 15 guide-bearings in head 3, after the disengagement of the presser-foot from the lower end of the presser-bar. The parts thus far described, and the arrangement thereof, are 20 not directly involved in the invention, and various changes may be made therein in practice, if deemed desirable.

I will now proceed to describe the parts which are more immediately involved in the 25 invention. A sleeve or block 10 is fitted upon the presser-bar 1, within the opening at the outer end of the head 3, and between the upper and lower guide-bearings for the presser-bar in the said head. The said sleeve 30 or block constitutes the body of the clamp which I employ. It has a sliding fit upon the presser-bar, to enable the sleeve or block and presser-bar to move vertically with relation to each other when not locked together. 35 At one side of the sleeve or block a slot 101, Fig. 3, is formed through the wall thereof, the said slot extending vertically throughout the greater portion of the length of the sleeve or block, and at opposite sides of the slot the 40 sleeve or block is formed or provided with projecting-cheeks 102, 102, which are parallel with each other. The cheeks receive between them lever-members comprising the clamping-lever 11 and the actuator-lever 12. 45 The said lever-members 11 and 12 respectively are provided with pivot-pins 111 and 121, respectively, the bearings of which are constituted by holes that are formed through the said cheeks. The pivot-pins occupy 50 holes that extend transversely through the said lever-members. For the purpose of enabling each lever-member to be tightened upon the pivotal pin which occupies the hole therein, so as to grip and hold the said pin in 55 place to guard against accidental endwise movement, a slit is made in the lever-member, leading from the exterior surface of the latter to the transverse hole, and a screw 112 or 122 is provided to draw the sides of the 60 slit toward each other, thereby contracting the said hole in diameter.

In the drawings, although not necessarily in the case of all embodiments of the different features of the invention, the clamping-lever 11 makes contact directly with the

presser-bar 1. See Fig. 3. Movement is transmitted to the primary or clamping-lever 11 from the secondary or actuator-lever 12, for the purpose of causing the presser-bar to be gripped by the clamp. The two lever-members 11 and 12 constitute in effect a compound lever. The arrangement of the said lever-members, and the mode and means of their operative connection or engagement with each other, may vary more or less in practice. The arrangement shown in the drawings is a convenient one. I usually place the two lever-members in operative connection or engagement with each other, for the purpose of transmitting movement 75 from the actuator-lever 12 to the clamping-lever 11, by means of a strut, as 131, Fig. 3, interposed between the said lever-members.

The said strut is shown formed with enlarged and rounded ends, the lever-members being 80 represented as formed with concave seats receiving the said ends, making knuckle-joints. Preferably, one or each of the seats in the lever-members is proportioned to take in somewhat more than half of the diameter 85 of the corresponding rounded enlarged end of the strut, the outer portions of the seat converging about the enlarged end somewhat so as to clasp the enlargement more than halfway round the same. This construction, 90

while permitting free working of the end of the strut in the seat during action, retains the said end within the seat, and prevents the strut from becoming detached and falling away, either during the operation of assembling the parts or when the parts are being handled in setting or adjusting the same. The strut is applied to the seat, formed as just explained, by passing the enlarged end of the strut edgewise into the seat, and also 100 is disengaged therefrom by an edgewise movement. The actuator-lever 12 is operated by means of a tappet 13 forming part of a rocker 14, which latter in the present instance, is conveniently arranged at the outer end of 105 head 3, the axis of the said rocker extending horizontally, parallel with and across the said outer end. The rocker is mounted upon center-screws 15, 15, which are applied to lugs 31, 31, extending outwardly from the 110 front and rear sides of the head 3. For the convenient actuation of the rocker in proper timing with the action of the other working parts of the machine it is in the present instance provided with an arm 16, Figs. 1, 2 115 and 4, which is sleeved upon the rocker and made fast thereto by means of clamping-screws 161, 161, Fig. 4, the said arm being joined by means of a link 17, Figs. 2 and 4, to ears projecting from one side of a collar 18 120 which is mounted upon a vertically reciprocating bar 19, herein serving as an awl-bar and carrying an awl 191. The bar 19 has connected therewith actuating devices of 125 suitable character, such devices in the pres- 130

ent instance comprising a link 20 having its lower extremity pivotally joined to the collar 18, aforesaid, and a hub 21, provided with a crank-pin having the upper extremity of the 5 link connected therewith, and mounted upon the operating shaft 22 which is supported in bearings in the arm or gooseneck 4, all substantially as usual. For the purpose of enabling the time of closing the clamp and beginning the lift of the presser-bar, and also 10 the extent of the lift of the presser-bar and presser-foot, to be regulated when desired, the rocker and tappet 13 are made angularly adjustable around the axis of motion of the 15 rocker. This adjustability is secured by flattening transversely, as shown in Fig. 2, the portion of the rocker 14 against which the inner ends of the clamping-screws 161, 161, bear, and by disposing the said clamping- 20 screws to make contact with the transversely extending flat surface of the rocker at opposite sides, circumferentially, of the middle of the said surface. By turning the respective screws more or less the rocker and its tappet 25 may be adjusted angularly with relation to the arm 16, and thereby the desired timing and extent of lift may be secured. To obviate any tendency to lateral displacement of the actuator-lever 12, the rocker and top of 30 the tappet 13 are grooved to receive the said actuator-lever. An expanding spiral-spring 23, encircling the presser-bar 1, is confined between the top of the sleeve or block 10 and the upper portion of the head 3. It acts 35 expansively with a tendency to move the clamp downward.

In operation, the rise of the awl-bar serves through the connections between the same and the rocker to turn the latter in a manner 40 to cause the tappet 13 to swing upwardly. In thus swinging, the said tappet presses upwardly against the actuator-lever 12. The rise of the clamp being resisted by the spring 23, the pressure of the tappet acts to turn the 45 actuator-lever upon its pivotal connection with the cheeks 102, 102, and close the clamp firmly against the presser-bar. Further movement of the actuator-lever upon the pivot-pin 121 being then impossible, the 50 clamp is raised bodily, carrying with it the presser-bar and presser-foot and compressing the springs 5 and 23. As the tappet swings downwardly after completing its upward movement, it lowers the clamp, presser-bar, 55 and presser-foot, which descend in unison until the presser-foot seats itself upon the material being operated upon. This relieves the clamp of the force exerted by spring 5, and relaxes the pressure of actuator-lever 12 against the tappet, the pressure still 60 remaining being only that which is due to the action of spring 23 and to the weight of the clamp. Thereby the hold of the clamp upon the presser-bar is relaxed, and the clamp is 65 permitted to follow the tappet 13 down. In

order to insure the complete release of the presser-bar, the actuator-lever is furnished with a heel 123 extending to the opposite side of the pivotal axis of the actuator-lever from the portion of the latter upon which the tap- 70 tap acts in clamping and lifting. As the parts complete their descent the said heel comes into contact with an inner portion of the tappet, thereby causing the actuator-lever to be turned so as to open the clamp 75 fully. The acting surface of the tappet makes rolling contact with the actuator-lever 12, and as the tappet completes its downward swing the said actuator-lever comes gradually to take bearing against the portion 80 of the tappet at its axis of movement, while in the upward swing of the tappet the lifting of the actuator-lever is gradually begun and continued. In consequence, the entire clamp is at all times supported on the tappet, 85 and blows, thumping, etc., resulting from play or lost-motion between the tappet and lever are obviated.

Preferably, the actuator-lever 12 and strut 131 are combined and arranged to act together on the principle of a toggle, in order to gain an increase of power. Still further power is secured by the employment of the secondary lever 11, and by causing the strut to engage therewith at a point so situated 95 with respect to the pivotal axis of such lever, and to the radial distance from such axis of the part which makes contact with the presser-bar, as to give effective leverage. This employment of a compound lever is of great 100 value, practically, inasmuch as it remedies deficiencies which exist when the clamp is provided with a simple actuator-lever or the like. It heretofore has been proposed to employ in a lifting arrangement, in combination with a toggle, a block actuated thereby 105 and in sliding in an opening in the side of the sleeve or block, to engage with the presser-bar. This construction gives an insufficient hold upon the presser-bar for some uses, and 110 is unreliable in its action in lifting the presser-bar, there being a tendency to slip. In case the toggle were set fine enough to overcome the tendency to slip, the toggle would lock and fail to release the clamp so as to permit 115 the latter to let go. The compound-lever arrangement characterizing my present invention enables ample power to be secured for perfect action, without it being necessary to cause the middle joint of the toggle to approach so closely to the line connecting the outermost joints as to occasion a tendency to lock.

The operative portion of tappet 13 extends from the axis of motion of the rocker toward 125 the presser-bar, and the arm of the actuator-lever that is engaged by the said tappet extends from the pivot of the actuator-lever in the same direction. This enables the lifting force which is transmitted from the up- 130

wardly swinging tappet 13 to act along vertical lines of transmission at the same side of the said pivot and axis, and also of the toggle-joint, as the presser-bar, closely adjacent the presser-bar. There is, in consequence, very little tendency during the lift to spring the presser-bar and cause the same to bind in its guide-bearings in the head of the machine. Hence, the resistance which 10 has to be overcome in raising the presser-bar and presser-foot, and the wear between the presser-bar and its guide-bearings, are not materially increased through this cause. The action, in other words, is rendered easier 15 than would be the case were the lifting tappet arranged to act at the opposite side of the pivot and axis aforesaid, the wear and tear of the presser-bar and its bearings are much less, and less strain devolves on the parts 20 through which the actuation of the lifting tappet is derived. The arrangement, also, is considerably more compact than it is possible to make one in which the lifting tappet and arm or lever engaged thereby extend outward from the presser-bar, inasmuch as a certain distance is necessary to be occupied in order to secure the length of levers, etc., requisite in attaining the required power in the clamping action, and in 25 30 attaining the required length of lift.

While I have herein shown and described the actuating tappet of the clamps as operated by the awl-bar of a sewing-machine, it is equally within the principle of my invention 35 to operate the said tappet by means of the needle-bar in a sewing machine in which the latter is mounted in the head thereof.

I do not claim herein, *per se*, the compound lever or the other broad and leading features 40 which have been described, for the same have been made the subject of claim in my application filed August 19, 1904, Serial No. 221,378.

I claim as my invention:—

45 1. In presser-foot lifting mechanism, the combination with the presser and presser-bar, of the clamp provided with the compound lever acting with multiplied leverage in effecting the grip and comprising a clamping-lever and an actuator-lever, both carried by the clamp-body, and means actuating the said actuator-lever and thereby operating the clamp to grip the bar and lift the presser-bar and presser.

55 2. In presser-foot lifting mechanism, the combination with the awl-bar or needle-bar, the presser, and the presser-bar, of the clamp provided with the compound lever comprising an actuator-lever and a clamping-lever, 60 both carried by the clamp-body, and the tappet operated by the awl-bar or needle-bar and actuating the said actuator-lever to oper-

ate the clamp and lift the presser-bar and presser.

3. In presser-foot lifting mechanism, the 65 combination with the awl-bar or needle-bar, the presser, and the presser-bar, of the clamp provided with the clamping-lever and with the toggle carried by the clamp-body and actuating the said clamping-lever, and the tappet 70 actuated by the awl-bar or needle-bar and operating the said toggle.

4. In presser-foot lifting mechanism, the 75 combination with the awl-bar or needle-bar, the presser, and the presser-bar, of the clamp provided with the compound lever carried by the clamp-body, and the tappet actuated by the awl-bar or needle-bar and transmitting to the said compound lever lifting force which acts along vertical lines 80 at that side of the pivot of the lever-member engaged thereby which is toward the presser-bar, to thereby actuate the clamp and lift the presser-bar and presser.

5. In presser-foot lifting mechanism, the 85 combination with the awl-bar or needle-bar, the presser, and the presser-bar, of the clamp provided with a clamping-lever and a toggle in operative connection with the said clamping-lever, both carried by the clamp-body, 90 and the tappet actuated by the awl-bar or needle-bar and transmitting to the said toggle lifting force which acts along vertical lines at that side of the toggle-joint or knuckle at which the presser-bar is located. 95

6. In presser-foot lifting mechanism, the combination with the awl-bar or needle-bar, the presser, and the presser-bar, of the clamp having a compound lever carried by the clamp-body, and the tappet operated by the 100 awl-bar or needle-bar and engaging with a member of the said compound lever to actuate the clamp and move the presser-bar endwise, the said tappet supporting the clamp at all times.

105 7. In presser-foot lifting mechanism, the combination with the awl-bar or needle-bar, the presser, and the presser-bar, of the clamp having a compound lever embracing a clamping-lever and an actuator-lever, both carried 110 by the clamp-body, and a tappet operated by the awl-bar or needle-bar, transmitting force to the actuator-lever at that side of the pivot of the actuator-lever at which the presser-bar is located to close the clamp and lift the 115 presser-bar and presser, and supporting the clamp at all times.

In testimony whereof I affix my signature in presence of two witnesses.

HENRY H. CUMMINGS.
